UNITED STATES PATENT OFFICE

ALFRED GODFREY CAMPBELL, OF SHERBROOKE, QUEBEC, CANADA

RAZOR

Application filed August 17, 1931. Serial No. 557,664.

This invention relates to improvements in safety razors.

At the present time safety razors have a very serious objection in that the angle of inclination of the blade, relatively to the face, has to be adjusted in the act of shaving by the user of the razor and in many cases this results in a drawing of the hair on the face and great discomfort to the shaver.

10 I have investigated this matter with the object of overcoming the objections usually met with in ordinary safety razor blades, and my invention particularly resides in the adapting of a blade to the proper angle of 15 inclination relative to the cheeks and to the neck of the user, so that the shaving will be accomplished by a steady, downward stroke, and it will not be necessary to jockey with the handle of the razor to adjust the blade to the 20 proper angle of inclination to the face to obtain a comfortable shave.

So that the nature of my invention will be clearly understood, I have illustrated a preferred embodiment of the same, but I do 25 not desire to be limited to the precise construction as I may find that it is necessary under some circumstances to slightly modify the angle of inclination of the blade, within the scope of my appended claims, in which 30 I have set forth the construction which I deem to be new.

In the drawing,

Fig. 1 is a side elevation of my improved razor.

35 Fig. 2 is an enlarged view of the blade holder.

Fig. 3 is a side elevation of a part of the blade holder.

40 Fig. 4 is a side elevation of my improved blade.

Fig. 5 is a side elevation of the outer support member of the holder.

Like characters of reference refer to like parts in the several figures.

45 Referring to the drawing,

A represents my improved razor comprising a handle portion 10, a guard 11 provided with teeth, and an outer blade support 12, the guard and outer blade support forming a 50 clamping means or holder for the razor.

blade. The guard 11 is provided with a central orifice 13 through which the stem 14 of the blade support 12 extends, and the guard is also provided with a pair of orifices 15 through which the pins 16 carried by the 55 member 12 extend.

The blade 17 is semi-rigid and bent along a median line, that is to say, a line adjacent to the centre of the blade, which, however, does not necessarily divide the blade into two 60 equal parts, as one section 18 of the blade may be shorter than the other section 19. The two sections 18 and 19 of the blade 17 are inclined to each other at an angle slightly greater than a right angle, that is to say, an 65 obtuse angle, but not an extreme obtuse angle; this blade 17 is also provided with orifices through which the pins 16 and the stem 14 of the member 12 extend.

By reference to the drawing, it will be 70 noticed that the two arms of the razor blade are arranged at different angles relatively to the longitudinal axis of the handle. The arm of the blade which is used for shaving the cheeks is arranged at approximately 30° 75 to 35° to the longitudinal axis of the handle, and the arm of the blade which shaves the neck and the throat is arranged at an angle approximately 60° to 70° to the longitudinal axis of the handle. 80

These inclinations of the sections of the blade are such that the cheek and the throat and neck may be shaved by the different sides of the razor blade while still maintaining a downward stroke on the handle. This is an 85 extremely important point of my invention, because, while I am aware that blades have been bent along a median line heretofore, I do not know of any blade ever having been bent and mounted in a manner in which the 90 sections of the blade are arranged at different angles of inclination such as I have described. The positioning of the blade is brought about by providing the orifices 20 and 21 off-centre from the median line on 95 which the blade is bent, that is to say, the major portion of these orifices lies in the longer section of the razor blade.

The angular formation of the guard 11, the blade support 12, and the blade 17 are 100

complementary so that the guard and support merely clamp the blade and do not distort it. When the blade is clamped in position the razor takes the position shown in Fig. 1, in which it is ready for use and the shorter section 18 is arranged at an angle relatively to the longitudinal axis of the handle 10 in which the cutting edge of the section 18 will meet the face of the user at the proper angle to permit of a direct downward stroke being applied to the razor without any adjusting of the handle relative to the face of the user. For the neck and throat the longer section 19 of the blade 17 is also at the proper angle of inclination to the longitudinal axis of the handle 10 permitting a steady downward stroke, and it will be understood that the handle 10 will never be at right angles to the face or form an extreme angle to the face of the user, but will be more or less in parallelism with that portion of the face which is being shaved, so that, in this way, a downward stroke is permitted to provide a comfortable shave to the user.

25. What I claim as my invention is:

1. In a safety razor, a handle, a guard, a support, a blade interposed between the guard and support, said guard, support and blade each permanently bent upon a lengthwise median to provide a pair of oppositely extending permanently inclined parts, the angle of inclination of a part of each pair being greater relative to the axis of the handle than that of the other part of the pair, one of the parts of the guard and of the blade adjacent the bends of the guard and blade being formed with spaced orifices, one of the parts of the support adjacent the bend of the support being provided with spaced holdfast elements extended through the orifices in the guard and blade, one of said elements being elongated for anchoring in an end of the handle to couple the guard, blade and support in position, and said bonds being arranged in superposed relation.

2. In a safety razor, a handle, a guard, a support, a blade interposed between the guard and support, said guard, support and blade each permanently bent upon a lengthwise median to provide a pair of oppositely extending permanently inclined parts, the angle of inclination of a part of each pair being greater relative to the axis of the handle than that of the other part of the pair, one of the parts of the guard and of the blade adjacent the bends of the guard and blade being formed with spaced orifices, one of the parts of the support adjacent the bend of the latter being provided with spaced holdfast elements extended through the orifices in the guard and blade, one of said elements being elongated for anchoring in an end of the handle to couple the guard, blade and support in position, said bonds being arranged in superposed relation, the parts of the guard, blade and

support having the greatest angle of inclination being of less width than said other parts, said orifices being arranged in the parts of the guard and blade of greatest width, and said holdfast means being extended from the inner face of the part of greatest width of said support.

3. In a safety razor, a handle, and an angle shaped blade connected with one end of said handle, said blade being formed with a pair of oppositely extending, permanently inclined parts, each of said parts having a cutting edge, one of said parts being disposed at an angle of approximately 60 degrees with respect to the axis of the handle and the other of said parts being disposed at an angle of approximately 30 degrees with respect to the axis of the handle, said one part being of greater width than said other part.

4. In a safety razor, a handle, and an angle shaped blade connected with one end of said handle, said blade being formed with a pair of oppositely extending, permanently inclined parts, each of said parts having a cutting edge, one of said parts being disposed at an angle of approximately 60 degrees with respect to the axis of the handle and the other of said parts being disposed at an angle of approximately 30 degrees with respect to the axis of the handle, said one part being of greater width than said other part, and said part of greatest width being provided with spaced orifices for the passage of holdfast means for anchoring the blade to the handle, said orifices being arranged in proximity to the point of emergence of the said parts.

5. A safety razor blade having substantially rigid plane portions, each of said portions having a cutting edge, said portions being inclined at an angle to each other, and one of said portions being wider than the other and having lug receiving apertures.

Signed at Biddeford, Maine, this 30th day of July, A. D. 1931.
